UNITED STATES PATENT OFFICE

LOTT D. OLIVER, OF HOUSTON, TEXAS

BRICKMAKING MACHINE

Application filed February 18, 1928. Serial No. 255,429.

This invention relates to new and useful improvements in a brick making machine.

One object of the invention is to provide a brick making machine, a novel type of mould, whereby a plurality of brick may be pressed, or moulded, in a unit, with weakened lines along which the unit may be easily broken up into individual brick, having roughened, or irregular faces.

Another object of the invention is to provide, in a brick press, a mould having means for forming weakened lines separating the brick, of which a moulded unit is composed so that the unit may be easily broken into individual brick, said means being of such disposition as not to interfere with the removal of the moulded unit from the mould.

A further feature of the invention resides in the provision of means, associated with the press for ultimately separating the moulding units, along said weakened lines, into individual brick, or building units.

With the above and other objects in view this invention has particular relation to certain novel features of construction, operation and arrangement of parts, an example of which is given in the specification and illustrated in the accompanying drawings wherein:

Figure 1 shows a longitudinal vertical sectional view of the mould.

Figure 2 shows a plan view thereof.

Figure 3 shows a sectional view of the mould with the cover removed.

Figure 4 shows a longitudinal vertical sectional view of the mould, showing the cover disposed above the mould box, and illustrating the parts in position for discharging the pressed unit from the mould.

Figure 5 shows a perspective view of the pressed unit composed of a plurality of brick integrally joined together.

Figure 6 shows a perspective view of an individual brick produced from said mould.

Figure 7 shows a fragmentary side eleva-

tion of the apparatus for separating the moulded unit into individual bricks.

Figure 8 shows a vertical sectional view thereof, and

Figure 9 shows a horizontal sectional view 50 of the complete machine.

Referring now more particularly to the drawings, wherein like numerals of reference designate similar parts in each of the figures, the numeral 1 designates the mould box, of 55 rectangular contour and having the sides 2, 2 and the ends 3, 3. The sides 2 of the mould box have the opposed inside vertical ribs 4, 4, which continue across the bottom 5, of the box, forming the transverse bottom rib 6. 60 The ends 3 of the box, have the inside oppositely disposed ribs 7, 7, and the bottom 5, has a lengthwise bearing slot 8 aligned with the ribs 7.

There is a plunger 9 forming the top or 65 cover for the mould, and which is adapted to fit closely into the mould box and whose under side has the transverse and lengthwise ribs 10, 11 aligned with the respective ribs 4 and 7.

There is a lengthwise blade 12, adapted to work through the bearings slot 8. The upper edge of this blade is beveled to an edge, as is also the free edges of the ribs 4, 6, 7, 10 and 11. The bottom 5, of the box is fixed to the upper 75 ends of side arms 13, 13 which, in turn, are mounted on the vertically movable table 14, while the mould box 1 is fixed on the frame 15, of the press. The blade 12 is mounted on the coil springs or other yieldable seats 16, 80 which in turn are supported by the table 14, and normally the sharp edge of said blade projects above the upper surface of the mould bottom 5 with the stops 17, carried by the said blade resting against the under side of 85 said bottom.

Fastened to, and depending from the blade 12 are the tubes 18, 18 which extend down through the openings 19, 19, in the table 14. The lower ends of these tubes have the bear- 90

ing glands 20, 20, screwed therein having central bearings through which the release rods, 21, 21 work. The upper ends of these rods, within the tubes 18 are enlarged, forming plungers 22, 22 and the lower ends are attached to a stationary part 23, of the press.

In operation the mould box is filled with plastic clay, or other material of which the brick is to be formed and the cross head 24, 10 carrying the plunger is then lowered, by the conventional mechanism, of the press, to compact said material. The unit 25, as thus compacted, will have oppositely disposed vertical side grooves formed by the ribs 4 and 15 the aligned top and bottom transverse grooves formed by the ribs 6 and 10; also the lengthwise top and bottom grooves, and the connecting end grooves, formed by the ribs 11, the blade 12 and the ribs 7, 7.

20 When the material is sufficiently compressed the plunger 9 is elevated and the bottom 5 is raised, by the table 14, until its upper surface is flush with the top of the mould box. As the table is raised the blade 12 will move 25 upwardly with it until the glands 20 contact with the lower ends of the plungers 22 and the upward movement of said blade will be arrested but the bottom will move on upwardly until the compressed unit 25 clears 30 the upper edge of said blade, and said unit may be then discharged laterally from the bottom of the mould box, onto the adjacent platform 26.

For the purpose of discharging the compressed unit 25 from the mould box onto the platform 26 a plunger 27 is provided which is operable through the connecting rod 28, one end of which is pivoted to the plunger 27 and whose other end has an eccentric connection with the constantly rotating driving disc 29, which is fixed on the drive shaft 30. The movement of the plunger 27 is so timed that it will come into contact with the successive units 25, as they are elevated from the mould box and automatically transfer them onto the platform 26.

50 Mounted on this platform 26 are the end guides 31, 31 which are located inside of the respective transverse spring seats 32, 32 which are fixed to the ends of the platform 26 and interposed between the guides 31 and corresponding seats 32 are the coil springs 33. The guides 31 are fastened to the platform 26 by means of set bolts 34 which are fitted through oblong slots 35, of the outwardly turned flanges 36, of said guides, and are 55 screwed into the platform 26 beneath.

60 The platform 26 has the lengthwise and transverse slots 37, 38 cut therethrough, located so as to align with the corresponding lengthwise and transverse grooves in the underside of the moulded unit thereon and the guides 31 are provided to insure such alignment and to hold the unit securely in place 65 on the platform 26 while it is being separated

into individual brick, as hereinafter explained.

Underneath the platform 26 are the lengthwise and transverse blades 39, 40 which are integrally joined together at their centers and which are aligned with the corresponding slots 37, 38. These blades form a unit which is enclosed within the housing 41 which is bolted to the underside of the platform 26. The unit formed by the blades 39, 40 has central, upstanding pilot spike 42, for a purpose to be hereinafter stated. 70 75

The housing 41 has a central vertical bearing 43 through which the rod 44 works. The upper end of the rod is attached to and supports the unit formed by the blades 39, 40. This rod has an adjustable spring seat 45, thereon and mounted on this seat and interposed between it and the housing 41, and surrounding the rod 44 there is a coil spring 46 which normally holds the blades 39, 40 retracted, that is withdrawn with their edges slightly beneath the upper surface of the platform 26.

The rod 44 and spring 46 are enclosed by means of the hood 47 which is bolted to the underside of the housing 41 and which has the lower end bearing 48 through which said rod 44 also works.

The lower end of the rod 44 abuts the U-shaped bracket 49, the free ends of whose arms are outwardly turned, forming the bearings 50, 50 and bolted to the underside of the platform 26 are the bearing members 51, 51 to which the respective arms 52, 52 are pivoted. The inner ends of these arms are upturned and work underneath and in contact with the respective bearings 50 and their outer ends are connected to the free ends of the corresponding side arms 53, 53 of the inverted U-shaped bracket 54. This bracket 54 has a central bearing 55 in which the lower end of the thrust rod 56 is fastened and fastened to the under side of the bearing 55 are the lengthwise and transverse blades 57, 58, aligned over the corresponding blades 39 and 40. The blades 57, 58 form a unit having the central depending pilot spike 59 for a purpose to be hereinafter explained.

There is an upright support 60 to the front 11 face of which the supporting plate 61 is bolted and secured to the lower end of the plate 61 there is an enclosing hood 62 having aligned upper and lower end bearings 63, 64 through which the rod 56 works. Within 12 the housing 62 there is an adjustable spring seat 65 and between this seat and the lower end of the housing 62 there is a coil spring 66, which normally holds the blades 57, 58 spaced above the unit to be separated. 12

The upper end of the rod 56 is formed with a head 67 which is aligned underneath and normally spaced from a similar head 68 carried by the lower end of the rod 69. This rod 69 works through the upper and lower 130

end bearings 70, 71 of the housing 72 which is bolted to the upper end of the supporting plate 61. Attached to the rod 69, within the housing 72 there is a stop 73 which limits 5 the downward movement of the rod 69 and above this stop the rod 69 carries an adjustable spring seat 74. On this seat and surrounding said rod there is a coil spring 75 whose upper end bears against the upper end 10 of the housing 72.

The upper end of the rod 69 carries a cross pin 76 with the ends of which are spaced cams 77, 77, fixed on the shaft 78, successively contact. The shaft 78 rotates in the bearings 15 79, 79, which are fixed to the upper part of the support 60. The shaft 78 is constantly rotated to the end that the cams 77 will alternately elevate the rod 69 to place the spring 75 under compression and then release said 20 rod to the influence of said compressed spring.

When the rod 69 is so released the spring 75, assisted by gravity, will impart a downward thrust to the rod 69 and the head 68 25 carried thereby will strike the head 67 underneath and this will drive the blades 57 and 58 downwardly into the corresponding grooves in the upper face of the unit 25 underneath, the pilot spike 59, first entering the 30 upper face of the unit at the junction of said grooves. At the same time a downward thrust will be imparted to the bracket 54 and it will act through the arms 52 and bracket 49 to impart an upward thrust, through the 35 rod 44, to the blades 39, 40 and force them into the unit 25 along the lengthwise and transverse grooves in the under face thereof, and the pilot spike 42 first entering the unit at the junction of said last mentioned grooves.

40 The mechanism is so timed that the blades will be successively actuated only as the units 25 are successively delivered onto the platform 26, from the mould box and is further so timed that the upper and lower blades 45 will operate against the moulded units at exactly the same time. The pilot spikes and blades will thus separate each unit 25 along the weakened lines into individual brick which may then be removed from the platform 50 26 manually or by any suitable means provided for the purpose. As the unit is thus separated by the blades the guides 21 will yield outwardly as the individual brick are moved apart endwise.

55 While I have shown what I now consider the preferred form of the device it is obvious that mechanical changes may be made therein, and equivalents substituted for the parts shown and I reserve the right to make such 60 changes and modifications in the mechanical structure as may be comprehended within the scope of the appended claims.

What I claim is:—

65 1. A brick making machine including a platform, end guides thereon, said platform

having lengthwise and transverse slots there-through, lengthwise and transverse blades joined together and arranged in alignment with the slots underneath the platform, a central upstanding pilot spike carried by the 70 blade assembly, a depending rod attached to said blade assembly, a yieldable seat acting against said rod and arranged to normally hold the blades withdrawn from said slots, a U-shaped bracket abutting the lower end 75 of said rod and the free ends of whose arms are overturned forming bearings, pivotally mounted arms, one end of each of which works against the corresponding bearing, an inverted U-shaped bracket above the platform having side arms whose free ends are connected to the other ends of said pivotally mounted arms, lengthwise and transverse blades carried by said last mentioned bracket and aligned with said slots, said last 80 mentioned blades having a centrally located spike, a thrust rod supporting said last mentioned bracket, a yieldable member supporting said thrust rod and means for imparting thrusts successively to said thrust rod. 85

2. A brick making machine including a platform, end guides thereon, said platform having lengthwise and transverse slots there-through, lengthwise and transverse blades joined together and arranged in alignment 90 with the slots on one side of the platform, a central pilot spike carried by the blade assembly, a rod attached to said blade assembly, a yieldable seat acting against said rod and arranged to normally hold the blades withdrawn from said slots, a U-shaped bracket on said side of the platform abutting the outer end of said rod and the free ends of whose arms are overturned forming bearings, pivotally mounted arms, one end of each of which works against the corresponding bearing, an inverted U-shaped bracket on the other side of the platform having side arms whose free ends are connected to the other 95 ends of said pivotally mounted arms, lengthwise and transverse blades carried by said last mentioned bracket and aligned with said slots, said last mentioned blades having a centrally located spike, a thrust rod supporting said last mentioned bracket, a yieldable member supporting said thrust rod and means for imparting thrusts successively to said thrust rod. 100

3. A brick making machine including a platform, end guides thereon, said platform having lengthwise and transverse slots there-through, lengthwise and transverse blades joined together and arranged in alignment with the slots on one side of the platform, a rod attached to said blade assembly, a yieldable seat acting against said rod and arranged to normally hold the blades withdrawn from said slots, a U-shaped bracket on said side of the platform, abutting the outer end of said rod and the free ends of whose arms are over 110 115 120 125 130

turned forming bearings, pivotally mounted arms, one end of each of which works against the corresponding bearing, an inverted U-shaped bracket on the other side of the platform having side arms whose free ends are connected to the other ends of said pivotally mounted arms, lengthwise and transverse blades carried by said last mentioned bracket and aligned with said slots, a thrust rod supporting said last mentioned bracket, a yieldable member supporting said thrust rod and means for imparting thrusts successively to said thrust rod.

In testimony whereof I have signed my name to this specification.

LOTT D. OLIVER.
